(57) **CLAIM**

The ornamental design for a footrest, as shown and described.

DESCRIPTION

FIG. 1 is a perspective view of a footrest;

FIG. 2 is a front elevation view thereof;

FIG. 3 is a rear elevation view thereof;

FIG. 4 is a side elevation view thereof;

FIG. 5 is a top plan view thereof;

FIG. 6 is a bottom plan view thereof;

FIG. 7 is a perspective view depicting the footrest of FIG. 1 in an alternate collapsed position;

FIG. 8 is a front elevation view of the footrest in the alternate position;

FIG. 9 is a rear elevation view of the footrest in the alternate position;

FIG. 10 is a side elevation view of the footrest in the alternate position;

FIG. 11 is a top plan view of the footrest in the alternate position; and,

FIG. 12 is a bottom plan view of the footrest in the alternate position.

The broken line showing a person's legs in FIG. 1 are included for the purpose of illustrating the invention in use, and form no part of the claimed design.
